[57] CLAIM

The ornamental design for a table, as shown and described.

DESCRIPTION

FIG. 1 is a perspective view of a table, showing my new design;

FIG. 2 is a top plan view;

FIG. 3 is a typical side elevational view;

FIG. 4 is a bottom plan view;

FIG. 5 is a perspective view of a table, showing an alternate embodiment of my new design;

FIG. 6 is a top plan view of the alternate embodiment;

FIG. 7 is a side elevational view, the opposite side being identical thereto;

FIG. 8 is an end elevational view, the opposite end being identical thereto; and,

FIG. 9 is a bottom plan view thereof.
